UNITED STATES PATENT OFFICE.

NORRIS ELMORE CLARK, OF PLAINVILLE, CONNECTICUT.

EXPANDED METAL AND METHOD OF PRODUCING THE SAME.

No. 882,491.

Specification of Letters Patent. Patented March 17, 1908.

Application filed December 11, 1907. Serial No. 406,079.

To all whom it may concern:

Be it known that I, NORRIS ELMORE CLARK, a citizen of the United States, residing at Plainville, in the county of Hartford and State of Connecticut, have invented certain new and useful Improvements in Expanded Metal and Method of Producing the Same, of which the following is a specification.

10 My invention relates to expanded metal fabrics and particularly a new product and the method of manufacturing the same.

One object is to produce a material having tension members and anchors and suitable 15 for reinforced concrete constructions.

Another object is to provide a reinforcing material which cannot slip in the cement or concrete.

Another object is to provide a fabric which 20 will be itself reinforced or secured by the embedding material.

Another object is to make possible a method of manufacture which is economical and satisfactory.

25 Figure 1 is a plan view of a corner of a sheet of material prepared for expansion by my improved method. Fig. 2 is a view of the same expanded. Fig. 3 is a view of part of the same showing the elements in perspective. Fig. 4 is a sectional view on the plane of the line X X Fig. 3. Fig. 5 is a detail view.

The fabric consists of parallel series of beams 1, 2, 3, etc., connected to other parallel series of beams 4, 5, 6, etc. by strands 7, 30 8, 9, etc. in alternating or staggered arrangement. The ends of the beams, such as 10, 11 and 12 constitute offsets which preferably project beyond the line of strands 7, 8, and 9. When the material is used as concrete reinforcement this affords additional security 40 against bending of the beams by tension on the strands. The strands together with the connected portions of the beams constitute tension members extending lengthwise of the

45 web of the fabric while the beams constitute anchors substantially at right angles thereto. In the drawing I have shown the outer tension member as made up of strands such as 13 and 14 and intermediate anchors such as 15, but with no parts corresponding to the beams 4 and 5.

The stock is prepared for expansion preferably by slitting or lancing as shown in Fig. 1. This may be accomplished easily by suitable mechanism consisting for instance of

two transverse rows of double edged cutters corresponding to the beams 1, 1 and 4, 4. The stock is then fed and the beams 2, 2 and 5, 5 severed. As the material is fed forward step by step the succeeding rows of beams are 60 outlined and the longitudinal slits 16 and 17 separate the beams 1 from 1 and 4 from 4, etc. I reserve my right to claim this slitting mechanism in another application. During the slitting operation indentations 65 may be made at the ends of the strands 7, 8, 9, etc. so that the elements will more uniformly take up their proper positions in expanding. The slits resemble a number of interlaid letter H's, while the slotted material is 70 seen to be made up of staggered series of parallel beams 1, 4, etc. connected by parallel strands 7, 8, etc.

The strands of any one column, as for instance 7, 8, and 9 (Fig. 1), are united at their 75 ends, and taken together constitute a flexible zig-zag strip capable of extension. The next adjacent column of strands, such as 13, 14, etc., constitutes another zig-zag strip disposed in a direction opposite to the other 80 zig-zag.

After slitting, the sheet is stretched or expanded by suitable mechanism, for instance jaws engaging the four edges of the sheet and arranged to move radially outward relative 85 to the center of the sheet. The expansion which takes place increases the superficial dimensions of the sheet longitudinally and laterally as well. This method of expansion in two directions by stretching, is so far as I 90 am aware, entirely novel. It is easier to allow for such action than the customary action of contraction which takes place in other expanding methods. The mechanism for carrying this into effect, as above referred to, 95 I reserve for another application. Ordinarily no material is removed in slitting the sheet.

What I claim is:

1. An expanded metal fabric consisting of 100 connected bent strands forming tension members having offsets and short straight beams forming anchors in staggered arrangement.

2. An expanded metal fabric consisting of 105 connected strands forming tension members and short beams forming anchors in staggered arrangement, the ends of the beams extending beyond the tension members.

3. An expanded metal fabric consisting of 110

staggered series of beam members short strands connecting the beam members and offsets at the points of connection.

4. An expanded metal fabric consisting of 5 staggered series of beam members and short strands connecting the beam members, the strands being connected to the beam members at points short distances from the ends of the beam members.

10 5. An expanded metal fabric consisting of parallel series of short straight beams and strands with offsets connecting the beams in staggered relation.

6. An expanded metal fabric consisting of 15 staggered series of parallel beam members and alternate strands connected to opposite lateral portions of adjacent beams.

7. An expanded metal fabric consisting of 20 staggered series of beam members, connected by short strands, each end of each beam having a projecting portion to which the ends of two strands are connected.

8. An expanded metal fabric consisting of 25 parallel series of short staggered beams and short strands connecting the adjacent ends of the relatively staggered beams, the width of each strand being uniform from beam to beam.

9. The method of forming a metal fabric 30 which consists in slitting a sheet to form series of parallel beams in staggered arrangement separated by parallel strands connected alternately to the beams on each side and then stretching the sheet in two directions.

35 10. The method of forming a metal fabric which consists in forming double rows of transverse staggered slits, slitting the stock

longitudinally between the ends of the transverse slits and then stretching the sheet.

11. The method of forming a metal fabric 40 which consists in slitting the stock in the pattern of interlaid letter H's and then stretching the sheet.

12. The method of forming a metal fabric which consists in slitting the sheet so as to 45 form relatively staggered series of beams connected by strands in staggered arrangement, and then stretching the sheet laterally and longitudinally.

13. The method of forming a metal fabric 50 which consists in slitting a sheet so as to form oppositely disposed extensible zig-zag strips connected by beams, and then stretching out the strips, and separating the beams and forming openings.

14. The method of forming a metal fabric which consists in slitting a sheet so as to form oppositely disposed extensible zig-zag strips connected by beams and then separating the strips laterally, turning them on edge, and 60 forming openings.

15. The method of forming a metal fabric which consists in slitting a sheet so as to form oppositely disposed extensible zig-zag strips connected by beams, and then stretching out 65 the strips and separating them laterally so as to form openings.

In testimony whereof I affix my signature in presence of two witnesses.

NORRIS ELMORE CLARK.
